Primary Examiner — Joseph Kukella*Assistant Examiner* — Darryl J Dardenne(74) *Attorney, Agent, or Firm* — Mark E. Bandy; Rankin Hill & Clark, LLP(57) **CLAIM**

The ornamental design for a coffee machine, as shown and described.

DESCRIPTION

FIG. 1 is a right side view of a coffee machine.

FIG. 2 is a front view of the coffee machine of FIG. 1.

FIG. 3 is a left side view of the coffee machine of FIG. 1.

FIG. 4 is a rear view of the coffee machine of FIG. 1.

FIG. 5 is a front right perspective view of the coffee machine of FIG. 1.

FIG. 6 is a top view of the coffee machine of FIG. 1; and, FIG. 7 is a bottom view of the coffee machine of FIG. 1. The broken lines are directed to environment and are for illustrative purposes only; the broken lines form no part of the claimed design.
